(57) **CLAIM**

The ornamental design for a compensator, as shown and described.

DESCRIPTION

FIG. 1 is a perspective view of the compensator;

FIG. 2 is a front elevational view of the compensator;

FIG. 3 is a rear elevational view of the compensator;
FIG. 4 is a left-side elevational view of the compensator;
FIG. 5 is a right-side elevational view of the compensator;
FIG. 6 is a top plan view of the compensator;
FIG. 7 is a bottom plan view of the compensator;
FIG. 8 is a front elevational view of an internal structure of the compensator, which is a mirror image of the rear, right side, and left side views;
FIG. 9 is a perspective view of an alternate embodiment of the compensator;
FIG. 10 is a front elevational view of the alternate embodiment of the compensator;
FIG. 11 is a rear elevational view of the alternate embodiment of the compensator;
FIG. 12 is a left-side elevational view of the alternate embodiment of the compensator;
FIG. 13 is a right-side elevational view of the alternate embodiment of the compensator;
FIG. 14 is a top plan view of the alternate embodiment of the compensator;
FIG. 15 is a bottom plan view of the alternate embodiment of the compensator;
FIG. 16 is a front elevational view of an internal structure of the alternate embodiment of the compensator, which is a mirror image of the rear, right side, and left side views.
FIG. 17 is a perspective view of a second alternate embodiment of the compensator;
FIG. 18 is a front elevational view of the second alternate embodiment of the compensator;
FIG. 19 is a rear elevational view of the second alternate embodiment of the compensator;
FIG. 20 is a left-side elevational view of the second alternate embodiment of the compensator;
FIG. 21 is a right-side elevational view of the second alternate embodiment of the compensator;
FIG. 22 is a top plan view of the second alternate embodiment of the compensator;
FIG. 23 is a bottom plan view of the second alternate embodiment of the compensator; and,
FIG. 24 is a front elevational view of an internal structure of the second alternate embodiment of the compensator, which is a mirror image of the rear, right side, and left side views.
